United States Patent Office.

WILLIAM W. NORTON, OF DUNDEE, ILLINOIS.

Letters Patent No. 78,684, dated June 9, 1868.

IMPROVED MACHINE FOR THREADING THIMBLE-SKEINS.

The Schedule referred to in these Letters Patent and making part of the same.

TO ALL WHOM IT MAY CONCERN:

Be it known that I, WILLIAM W. NORTON, of Dundee, in the county of Kane, in the State of Illinois, have invented an Improvement in Screw-Cutting Machine for Thimble-Skeins; and I do hereby declare that the following is a full and exact description thereof, reference being had to the accompanying drawings, and to the letters of reference marked thereon, making a part of this specification, in which—

Figure 1 is a plan view of my invention.

Figure 2 is a longitudinal elevation of the same, with the frame which supports the gearing broken away.

Figure 3 an elevation of the device for holding one end of the skein.

This invention relates to a machine which is especially designed for cutting screw-threads on the ends of thimble-skeins, and for this reason it has a simple construction, and so that it may be used by persons having ordinary knowledge of this kind of mechanical work; and its nature consists in the use of a substantial iron bed-plate, to which are rigidly attached two upright metal standards, arranged to support the gearing, and a dove-tail guide, on which is made to operate an adjustable slide, supporting a head, and having fixed to it a removable device for holding the larger end of the skein in position when the screw-threads are being cut; and further, in an adjustable lever, arranged to slide on a rod attached to said bed-plate, and used to operate the adjustable slide when holding the skein in or removing it from the machine; and the use of a lever pivoted to lugs attached to the bed-plate, and arranged to operate the dies which cut the screw.

In order to give a correct understanding of my invention, I have marked corresponding parts with similar letters, and will now give such a detailed description as will enable others skilled in the art to make and use it.

A represents an iron bed-plate, having cast solid to it, or otherwise rigidly fastened, two standards I I, for supporting the gearing K K V, which operates the die-shaft J, and a dove-tail guide, A'', on which a slide, A', is made to have a reciprocating motion longitudinally, for the purpose of holding skeins of different lengths and removing them from the machine. And to accomplish this, the slide A' is made to terminate in a vertical head, B, and the latter to support a device, G, which holds the large end of the skein in the machine. This device is made of cast metal, and with a projecting lug, H, of such size and shape as will fit the hole in the skein, and thus hold it in place while the screw-thread is being cut.

I use such a number of these devices as will correspond with the different sizes of the skeins, and fasten them to the head B by means of bolt a. A rod, C, is rigidly attached to one side of the bed-plate A, and made to support a slide, D, held in place by a set-screw, e. Said slide is jointed to a lever, E, used to move the slide A', and also to hold the thimble-skein U in place. A hook, F, being attached to the head B, provides a support for one side of the lever, and said head the other side.

The arrangement for moving the dies is as follows: An elbow-lever, L, is made to turn in lugs M M, cast solid to the bed-plate A, and to support a standard, N, attached to said lever between the lugs, and made to lock in a groove in a collar, O. This collar is made to slide on a shaft, J, by bearing down or raising up said lever L, and thus move the connecting-rods T, which operate the levers P, and move the dies S, which cut the thread. All parts of the machine, including the die-head Z supported on the shaft J, I consider common and well known, therefore do not claim them as a part of my invention.

The drums K K are supported by standards I I, as is also the shaft J, they being also well-known devices used for giving motion to the die-head Z.

Operation.

The set-screw e can be loosened, and permit the slide A to be moved, so as to adjust the head B to any length of skein; it can then be fastened, and the lever E brought to bear against said head, and thus hold the skein in place. The dies can be opened and shut at the required time by means of the lever L.

Having thus described my invention, what I claim, and desire to secure by Letters Patent of the United States, is—

1. The improved machine for threading thimble-skeins, consisting of the parts herein specified and shown, all constructed and arranged as described.
2. The device G, with the lug H thereon, the slide A' having a head, B, the rod C, slide D, lever E, and hook F, all constructed and arranged substantially in the manner set forth.

WM. W. NORTON.
